Fig. 3.

UNITED STATES PATENT OFFICE.

NATHAN M. STONE, OF CHICAGO, ILLINOIS.

LOCK.

Application filed January 18, 1926. Serial No. 81,881.

This invention relates to locks, and its principal object is to provide a simple and inexpensive, yet practical and effective lock. The invention relates, more particularly, to that type of lock adapted for locking the lid or cover to a box, case, cabinet or the like. Another object is to reduce, to a minimum, the number of parts composing the lock. Another object is to provide a lock of which the several parts may be formed of metal stampings. Other objects and advantages will appear in the course of this specification, and with said objects and advantages in view, this invention consists in the several novel features of construction and arrangement of parts, hereinafter fully described and claimed.

The invention is clearly illustrated in the accompanying drawings, in which:

Fig. 1 is a front elevation of a lock embodying a simple form of the present invention; Fig. 2 is a rear elevation thereof; Fig. 3 is a rear elevation with the side flanges of the back member of the case shown in section; Fig. 4 is a view similar to Fig. 3, but showing the parts in locked position; Fig. 5 is a plan of the lock with the hook member removed; Fig. 6 is a horizontal section taken on the line 6—6 of Fig. 4 and Fig. 7 is a vertical section taken on the line 7—7 of Fig. 3 and showing the lock applied to a box. Figs. 3 to 7, inclusive, are upon an enlarged scale.

Referring to said drawing, the reference character A designates a box or cabinet and B the lid thereof to which the lock is applied. The character 10, designates the case of the lock, which may be rectangular in form, comprising the front case member 11 and the back case member 12. The front case member is formed with a marginal flange 13 and the back case member is formed with side flanges 14 that fit between the side flanges of the front case member and bear against the front wall 15 of said front case member. Tongues 16 are struck up at the edges of the flanges of the front case member and are bent over behind the back wall 17 of the back case member and secure said members together. Tongues 18

are struck up from the back case member and are adapted to be thrust through the wall of the object upon which the lock is used and bent down on it to secure the lock thereto. The case contains the operative parts of the lock and certain of its marginal walls act as guides for guiding the operative parts in their movements in the case.

The operative parts of the lock comprise a slidable lock plate 20, a slidable tumbler 21 and a U spring 22 carried by the tumbler and interposed between the lock plate and tumbler. A button 24 having a shouldered neck 25 extending through a slot 26 in the front wall 15 of the case and secured in a hole in the lock plate 20, furnishes means for retracting the lock plate from its locked position, and a key 27 (see Fig. 4), capable of being inserted through a keyhole slot 28 in the front wall of the case, furnishes means for actuating the tumbler in locking and unlocking the lock plate. A hook member 29 secured to the lid or cover of the object to which the lock is applied, is arranged to enter through a slot 30 in the top flange of the front case member and lockingly engage with the lock plate 20.

The lock plate 20 preferably comprises a metal stamping, struck up by suitable dies from sheet metal, and is, roughly speaking, generally rectangular in shape. Its upper edge bears against the underside of the top flange of the front case member, and said edge is held in engagement with said flange by the neck 25 of the button 24 which is confined in the slot 26. A wide notch 31 is formed in the upper half of the lock plate for the reception of the hook of the hook member 29 and said notch is so shaped as to leave a hook 32 on the lock plate, that lockingly engages said hook member 29 when in operative position.

At one side of the hook 32 the lock plate is formed with an arm 33 which projects beyond the side edge 34 of the lock plate, and said side edge 34 is formed, between its ends, with a rounded lug 35 against which one end of the U spring 22 is adapted to bear. The tension of the spring is exerted to yieldingly hold the lock plate in the posi-

tion seen in full lines in Figs. 3 and 4, although permitting the lock plate to be moved over into the position indicated by the dotted lines in Fig. 3, to thereby release the hook member 29 from it. When the tumbler is in the position seen in Fig. 3 the lock plate is free to move back and forth, in a line lengthwise of itself.

The tumbler 21, is also a metal stamping somewhat L shaped in form, having a vertical arm 36 which bears against a side flange of the back case member and a horizontal arm 37 that projects from the vertical arm 36 toward the middle of the case. The 10 U spring stands in the angle, formed between the arms 36, 37 and one arm 38 of the spring extends up from its U bend and engages with a lug 39 formed on the arm 36 of the tumbler. The other arm 40 of the U 15 spring is bent up to form a rounded end 41 which engages the edge 34 of the lock plate, and when the parts are in the positions seen in Fig. 3 said rounded end of the spring engages the under side of the lug 35, 20 thereby yieldingly holding the tumbler in its unlocked position as seen in Fig. 3, and thereby permitting the lock plate to be retracted. It is to be observed that the upper end portion 42 of the vertical arm 36 of the 25 tumbler is located below the path of movement taken by the projecting arm 33 of the lock plate, when the tumbler is in unlocked position, thereby permitting free movement of the lock plate, but that when the tumbler 30 is moved into its raised or locked position (see Fig. 4) said end portion 42 stands in the path of movement of the projecting arm of the lock plate and effectively prevents movement thereof in the direction to release the hook member 29. It will also be observed that the U spring is secured between the upper curved edge 43 of the horizontal arm 37 of the tumbler and the lower edge of the lug 39 of the tumbler, and moves 35 with the tumbler, and that when the tumbler is moved into its raised or locked position, the rounded end 41 of the arm 40 of the U spring is engaged with the upper edge of the lug 35, thereby holding the tumbler 40 in its raised or locked position. The one and the same spring, therefore, acts to yieldingly hold the lock plate in its operative position for engagement with the hook member 29, and holds the tumbler in sliding engagement with the side flange of the case, and yieldingly holds the tumbler in its lower or unlocked position and in its raised or locked position.

The end of the horizontal arm 37 of the 50 tumbler is formed with a notch 44 in which the key 27 may engage to raise or lower the tumbler.

The operation of the lock is readily apparent from the above description. When 55 the key is inserted in the keyhole and turned

in the direction to lock the lock, the key engages with the upper edge of the notch 44 in the tumbler and raises the latter into the position seen in Fig. 4, wherein the end portion 42 of the vertical arm of the tumbler 70 takes a position obstructing movement of the lock plate. In approaching this position the rounded end 41 of the U spring has passed over the lug 35 and has become engaged against its upper edge, thereby preventing the tumbler from being lowered except when moved by a proper key. In this position of the parts, the lock plate cannot be manipulated. To unlock the lock the key is inserted in the keyhole and turned in the 75 direction to lower the tumbler and it then engages with the lower edge of the slot 44 thereby moving the tumbler down, out of the way of the projecting arm 33 of the lock plate, and the spring is therewith moved 80 down by the lug 39 to the position where it engages with the underside of the lug 35, and prevents the tumbler from being accidentally moved upward.

I claim as new, and desire to secure by 85 Letters Patent:

1. A lock, comprising a case, having top, bottom and side walls, a slideable lock plate guided by the top wall of the case, a slideable L shaped tumbler guided by a side wall of 90 the case, and a U shaped spring carried by, and moving with, said tumbler and interposed between said lock plate and tumbler, said lock plate having a lug, co-operating with one arm of said spring to yieldingly 95 hold the tumbler in its locked and unlocked positions.

2. A lock comprising a case, having top, bottom and side walls, a slideable lock plate guided by the top wall, a slideable L shaped 100 tumbler guided by a side wall of the case, and a U shaped spring interposed between the lock plate and tumbler, said lock plate having a hook for engagement with a complementary hook member, a projection adapted for engagement with the tumbler and a lug adapted for engagement with the spring, and the tumbler having the end portion of one of its arms adapted for engagement with the projection of the lock plate, said tumbler having a lug formed on said arm arranged to engage with the spring and hold it between the lug and its other arm, and said spring having a rounded end arranged to engage, alternately, with the under and 110 upper side of the lug on the lock plate, to thereby yieldingly hold said tumbler in its raised and lowered positions.

3. A lock comprising a case, having top, bottom and side walls, a slideable lock plate 115 guided by the top wall of the case, and formed with a tumbler engaging arm, at one end, and with a spring engaging lug on one edge, a slideable L shaped tumbler, guided by a side wall of the case and movable trans- 120

versely of the lock plate, said tumbler having a lock plate engaging end and a spring engaging lug, and a U spring, held between said spring engaging lug of the tumbler and an arm of said tumbler, and moving with said tumbler, said spring having a bent up end engaging with the edge of said lock

plate on which the spring engaging lug is formed, and movable across said lug, said spring acting to yieldingly hold the lock 10 plate in locked position, and to hold the tumbler in its locked and unlocked positions.
